UNITED STATES PATENT OFFICE

WALTER DORWIN TEAGUE, OF FOREST HILLS, NEW YORK, ASSIGNOR TO TAYLOR INSTRUMENT COMPANIES, OF ROCHESTER, NEW YORK, A CORPORATION OF NEW YORK

DESIGN FOR A BAROMETER

Application filed August 11, 1931. Serial No. 40,822. Term of patent 3½ years.

To all whom it may concern:

Be it known that I, WALTER DORWIN, a citizen of the United States of America, residing at Forest Hills, county of Queens, State of New York, have invented a new, original, and ornamental Design for Barometers, of which the following is a specification, reference being had to the accompanying drawings wherein:

Fig. 1 is a front view of a design embodying my invention; and

Fig. 2 is a side view thereof.

I claim:

The ornamental design for a barometer, as shown.

WALTER DORWIN TEAGUE.
